UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 6, 1920. Serial No. 415,015.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to safety devices, 10 and its object is to prevent printing on the platen by the types during the time that case-shifting operations are in progress.

A feature of the invention relates to the provision of a device which is operative 15 during case-shifting movements to prevent printing by the types; but which is ineffective when the parts concerned in the case-shifting operations are in either of their extreme positions.

20 A further feature of the invention relates to the provision of locking means so arranged that the usual line-locking mechanism is utilized to prevent operation of the 25 keys during movements of the case-shifting means.

Other features and advantages will hereinafter appear.

In the accompanying drawings,

Figure 1 is a side elevation of a typewriting machine of the usual Underwood construction, showing my improvements applied thereto.

Figure 2 is a top plan view of a portion of the mechanism.

35 Figure 3 is a detail, showing the parts in a different position from that shown in Figure 1.

Referring to the drawings, key-levers 1 are adapted, through the medium of intermediate levers 2, to cause type-bars 3 to be moved upwardly and rearwardly against the front face of a platen 4. The type-bars 3 carry types 5 and 6 for printing lower and upper case characters, respectively, and, in order that either set of characters may be selected, the usual case-shifting means are provided. In the particular machine to which my improvements are applied, which machine may be of the 40 usual Underwood type, the platen is supported in a carriage, which carriage has a roller 7 running upon a guide rod 8, which guide rod is adapted to be engaged by rocking members 9 pivoted at 10, the rocking 45 movements of 9 being controlled by the

usual case-shift keys, one of which is shown at 11 in the drawings. Either one of the case-shift keys is adapted to rock the members 9 through the medium of an upwardly-extending finger 12.

In order to prevent any printing action of the types during the time the platen is being shifted. I provide means for locking said types during movements of the case-shifting means, and I do this preferably through the medium of the usual line-locking mechanism. This line-locking mechanism in the Underwood typewriter consists of a rod 13 pivoted in the lower front portion of the machine, to which rod 70 is fastened a rocking lever 14, one at each end of the rod. The upper ends of the rocking levers are connected by a key-locking bar 15, and a spring 16 is provided which normally tends to move the locking bar 15 75 away from projecting lugs 17 carried by the key-levers.

In order to utilize this mechanism for the purpose of the present invention, I provide a connection between the case-shifting means 80 and the bar 15 whereby the same is moved under the lugs 17 during case-shifting movements. To accomplish this, I preferably modify one of the rocking members 9 by providing an extension 18 thereon, which 85 has a pin-and-slot connection with a lever 19 pivoted at 20. This lever 19 is provided with a cam-member 21 adapted to engage a pin 22 on one of the rocking levers 14, the cam-member 21 being so shaped that it engages the pin 22 during the time the case-shifting parts are being moved from one extreme position to the other; but said cam-member does not bear against the pin 22 when the case-shifting means occupies 90 either extreme position. It will thus be seen that the operative cannot strike a key and print on the platen before the carriage is in its proper place, either in upper or lower case.

100 The usual line-locking bar 15 is normally out of the paths of the type-key-levers, but is moved into the paths of said levers to lock the same temporarily while the platen is shifting, and released at each end of the 105 platen-shift movement in either direction, so that the bar may return to normal position when the platen is in either of its extreme positions. The case-shifting means includes the hinged shift-rail member 9 for 110

shifting the platen, and a cam-device 21 connected to said shift-rail member for both setting and releasing the lock 15 during each swing of the shift-rail member, and a returning spring 16 for said lock, whereby the lock is returned by said spring to normal position at the end of each stroke of the shift-rail member in either direction.

Variations may be resorted to within the scope of the invention, and portions of the improvements may be used without others.

Having thus described my invention, I claim:

1. In a typewriting machine, the combination with a carriage, a platen, types having upper and lower case characters thereon, key-levers for driving said types to print, a lock to engage said key-levers, said lock forming part of a line-locking mechanism and normally out of the paths of said levers, and case-shifting means for determining whether said types shall print on said platen in upper or lower case, of a cam-member movable by said case-shifting means and effective on said lock during case-shifting movements, to move it into the paths of said levers, but releasing said lock, to permit the latter to return to normal position, when said case-shifting means is in either of its extreme positions.

2. In a typewriting machine, the combination with a carriage, a platen, types having upper and lower case characters thereon, key-levers for driving said types to print, a lock to engage said key-levers, said lock forming part of a line-locking mechanism and normally out of the paths of said levers, and case-shifting means for determining whether said types shall print on said platen in upper or lower case, of a

cam-member movable by said case-shifting means and effective on said lock during case-shifting movements, to move it into the paths of said levers, but releasing said lock, to permit the latter to return to normal position, when said case-shifting means is in either of its extreme positions; said case-shifting means including a hinged shift-rail member for shifting the platen, and said cam-member being connected to said shift-rail member for both setting and releasing the lock during each swing of the shift-rail member, and a returning spring for said lock, whereby the lock is returned by said spring to normal position at the end of each stroke of the shift-rail member in either direction.

3. In a typewriting machine, the combination with a platen, types having upper and lower case characters thereon, key-levers for driving said types to print, a lock for said key-levers, said lock comprising a pair of rocking levers, a rod connecting said levers adapted to be moved to prevent operation of said types, and case-shifting means for determining whether said types shall print on said platen in upper or lower case, of a pin on one of said rocking levers, and a cam-member adapted to engage said pin to move said lock to position to prevent operation of said types during movements of said case-shifting means, said cam-member so shaped as to engage said pin during the shifting movements of said case-shifting means, but ineffective in the extreme positions of said case-shifting means.

ALFRED G. F. KUROWSKI.
